UNITED STATES PATENT OFFICE.

FRANK M. PIERCE, OF CHICAGO, ILLINOIS, ASSIGNOR TO PIERCE WRAPPING MACHINE COMPANY, OF CHICAGO, ILLINOIS, A CORPORATION OF ILLINOIS.

SHUTTLE-LOCK.

1,242,371.

Specification of Letters Patent.

Patented Oct. 9, 1917.

Original application filed October 3, 1914, Serial No. 864,735. Divided and this application filed January 2, 1915. Serial No. 102.

To all whom it may concern:

Be it known that I, FRANK M. PIERCE, a citizen of the United States, and a resident of the city of Chicago, in the county of Cook and State of Illinois, have invented certain new and useful Improvements in Shuttle-Locks; and I do hereby declare that the following is a full, clear, and exact description of the same, reference being had to the accompanying drawings, and to the numerals of reference marked thereon, which form a part of this specification.

This invention relates to a shuttle and constitutes a division of my co-pending application for patent for "tire wrapping machines" filed October 3rd, 1914, Serial No. 864,735. This type of shuttle when used in the machine is adapted to be opened to permit insertion of an annular object thereinto which is to be wrapped, and then closed and rotated at a high rate of speed while the article is also moved therethrough, so that a paper wrapping, the paper being carried upon a reel mounted upon the shuttle, is applied upon the article helically there-around. In this invention the shuttle is of an improved form, permitting ready opening and closing of the hinged sections thereof to permit insertion and removal of an article to and from the same.

It is an object, therefore, of this invention to construct a shuttle for a wrapping machine embracing sections hingedly connected to one another and provided with locking means for locking the same in closed position, together with paper carrying means to carry a reel of paper for application to an article to be wrapped.

It is also an object of this invention to construct a shuttle consisting of hingedly connected sections, one provided with a spring impelled locking bolt with mechanism thereon adapted to engage means on the other of said sections when the shuttle is swung into closed position to automatically release said locking bolt from a retracted position, permitting the same to be impelled into locking engagement, thus locking the shuttle sections one to another. It is furthermore an important object of this invention to construct a shuttle provided with hinged sections which, when in closed position, afford a closed ring having an outer peripheral contact flange or sur-

face and equipped with automatically acting locking mechanism which locks said sections one to another when the same are swung into closed position. 55

It is finally an object of this invention to provide a shuttle simple in construction 60 and easily operated into an open or closed position.

The invention (in a preferred form) is illustrated in the drawings, and hereinafter more fully described. 65

In the drawings:

Figure 1 is a view in elevation of a shuttle equipped with locking means embodying the principles of my invention.

Fig. 2 is a detail section taken on line 70 2-2 of Fig. 1.

Fig. 3 is a detail section taken on line 75 3-3 of Fig. 2, showing the shuttle sections moving into a closed position.

Fig. 4 is a central section taken longitudinally through the shuttle locking mechanism with parts shown in elevation. 75

Fig. 5 is a fragmentary detail view illustrating a side elevation of the spring impelled locking bolt. 80

Fig. 6 is a detail view of the complementary member therefor on the other shuttle section.

As shown in the drawings:

The shuttle is an annulus in form, consisting of two sections denoted respectively as a whole by the reference numerals 1 and 2, of which the section 1, for the most part is of angular cross section, as clearly shown in Fig. 2, but which, at its ends, terminates 90 in centrally disposed tongues of metal, that at one end of the shuttle section being denoted by the reference numeral 3, and that at the other end by the reference numeral 4. Said shuttle section 2, is at its middle portion of T-section, but at its ends terminates in yoke portions 5 and 6, with the yoke portion 5, engaged upon the tongue 3, of the section 1, and pivotally connected thereto by means of a stud screw 7. The other 100 yoked end 6, of said shuttle section 2, is adapted to engage around the tongue end 4, of the shuttle section 1, and said latter interfitting members are apertured to receive the tapered end 8, of a locking bolt 9, projected through the registering apertures therein. Said bolt 9, is provided on its end with a hand wheel or actuating head 10,

and is mounted within an outstanding slotted sleeve or cylindrical member 11, provided with a web extension 12, which is secured to the face of the shuttle section 2, by means of a bolt 13. A rigid collar 14, is secured on said bolt 9, adjacent the tapered end 8, thereof, which has an outstanding pin 15, projecting outwardly therefrom through the slot provided therefor in the cylinder 11. A coiled spring 16, is wound about said bolt within said cylinder 11, and bears at one of its ends against said collar 14, and at its other end against the end wall of said cylinder, thus normally impelling the bolt into a locking position.

An angled plate 17, is secured upon the tongue end 4, of the shuttle section 1, by means of a screw bolt 18, and is provided with a key shaped slot 19, therein, adapted to receive the pin 15, of the locking bolt engaged therein. As clearly shown in Fig. 5, the end of the longitudinal slot in the wall of the cylinder 11, terminates in a cutaway portion, thus affording a curved shoulder 20, behind which the pin 15, is adapted to engage when the bolt is retracted and given a slight rotational movement. Secured upon the side face of the shuttle section 1, is a bolt 21, having journaled thereon a paper reel 22, carrying a roll of paper 23. Also secured upon the face of the shuttle section 1, adjacent the paper carrying reel 22, is a plate 24, projecting outwardly from which are a group of smooth pins 25, 26, 35 and 27, respectively, around which the strip of paper is trained, as clearly shown in Fig. 1, thus affording a tension device for the paper. From the tension device the strip of paper is led through a curved folder plate 28, which is also secured upon the face of the shuttle section 1, and from there around a guide roller 29, from which it is led to the article being wrapped.

The operation is as follows: The shuttle as used in a wrapping machine tracks upon its flat rim or contact surface upon the driving element so that the shuttle is rotated at a high rate of speed and the paper being drawn around the idler 50 roller 29, through the folder plate 28, from around the tension pins and the reel 23, is applied to the article. The object is of course moved at the time the wrapper is applied thereto to insure an application of 55 the wrapper for the entire length of the article, whether it be a long straight pipe, or a curved object, such as a tire. When the shuttle is at rest and it is desired to open the same to insert an article thereinto 60 or remove a wrapped article therefrom, the operator grips the hand wheel 10, and rotates the same a sufficient amount to swing the pin 15, which is rigidly connected with the locking bolt, out of engagement with 65 the enlarged inner end of the key shaped

slot 19, and then pulls outwardly upon the locking bolt, giving the hand wheel a final twist in the opposite direction of rotation to engage said pin 15, behind the shoulder 20. The shuttle section 2, may then be 70 swung outwardly about its pintle bolt 7, from the shuttle section 1.

In locking up the shuttle after an article has been inserted therein it is only necessary to swing the shuttle section 2, into closed position, whereupon the pin 15, on the locking bolt strikes into the outer end of the slot 19, of the plate 17, the edge of the slot being slightly chamfered off, as indicated by the reference numeral 30, in Fig. 6. This causes 80 the pin 15, to be thrust laterally from behind the projection 20, whereupon the strong compression spring 16, within the containing cylinder 11, impels the locking bolt outwardly so that the tapered portion 85 8, thereof engages through the registering apertures of the yoke portion 6, of the shuttle section 2, and the tongue portion 4, of the shuttle section 1, thus locking the same together and of course then the pin 15, of 90 the locking bolt is engaged in the enlarged end of the slot 19.

I am aware that various details of construction may be varied through a wide range without departing from the principles of this invention, and I therefore do not purpose limiting the patent granted otherwise than necessitated by the prior art.

I claim as my invention:

1. In a device of the class described, 100 hingedly connected interfitting sections, spring impelled locking means on one section adapted to lock said sections one to another in closed position, means holding said spring impelled locking means in inactive 105 position, and means automatically releasing said spring impelled locking means for movement into a locking position when the shuttle sections are swung from an open to closed position.

2. In a locking device of the class described, hinged sections adapted to interfit and having aligned apertures, a slotted sleeve rigidly secured to one section, a locking bolt in the sleeve having one end adapted to engage in the aligned apertures, a collar on the bolt in the sleeve limiting the locking movement thereof, a spring on said bolt in said sleeve bearing against the collar to normally hold the bolt thrust inwardly, a pin on the bolt extending through the slot in the sleeve, and a notch in the sleeve adapted to receive the pin therein to lock the bolt when retracted.

3. In a locking device of the class described, hinged sections adapted to interfit and having aligned apertures, a slotted sleeve rigidly secured to one section, a locking bolt in the sleeve having one end adapted to engage in the aligned apertures, a collar on the

5 bolt in the sleeve limiting the locking movement thereof, a spring on said bolt in said sleeve bearing against the collar to normally hold the bolt thrust inwardly, a pin on the bolt extending through the slot in the sleeve, a notch in the sleeve adapted to receive the pin therein to lock the bolt when retracted, and means secured to the other section adapted to engage said pin and adjust it 10 out of the notch to release the locking bolt when the sections are closed.

4. In a device of the class described hingedly connected sections, a spring impelled locking bolt on one of said sections, 15 said sections provided with interfitting apertured members to receive said locking bolt projected therethrough to retain the same

closed in locked position, a slotted plate on the other of said sections, means retaining said locking bolt in an inactive position, 20 and a pin mounted on said bolt adapted to engage said slotted plate to be released thereby from its inactive position, permitting the bolt to be projected through said apertured interfitting members when the sections are moved from open to closed position. 25

In testimony whereof I have hereunto subscribed my name in the presence of two subscribing witnesses.
